UNITED STATES PATENT OFFICE.

EDWIN TAYLOR, OF EDWARDSVILLE, KANSAS.

SACK-HOLDER.

SPECIFICATION forming part of Letters Patent No. 717,779, dated January 6, 1903.

Application filed October 14, 1901. Serial No. 78,591. (No model.)

To all whom it may concern:

Be it known that I, EDWIN TAYLOR, a citizen of the United States, and a resident of Edwardsville, in the county of Wyandotte and State of Kansas, have invented new and useful Improvements in Sack-Holders, of which the following is a specification.

My invention relates to devices for holding sacks or bags in position to be filled; and my invention may be applied to vegetable and fruit sorters, grain-spouts, and a variety of other apparatus for filling sacks.

The object of my invention is to provide means for securing sacks with their mouths open for filling and for quickly and easily releasing the sack when it is filled.

Reference is had to the accompanying drawings, in which—

Figure 1 is a front elevation of one of my sack-holders attached to a hopper of a potato-sorter. Fig. 2 is a top plan view of the same. Fig. 3 is a side elevation of the same. Fig. 4 is an enlarged detail view of the detent-spring.

1 designates a spout forming the lower portion of the hopper 2. The sides of the spout are upright, as shown. Mounted in bearings 3 on each side of the spout 1 is a rock-shaft 4, having a plurality of spurs 5 projecting therefrom. The function of these spurs is to engage the upper part of the sack for sustaining the sack while it is being filled. Said spurs may be integral with the rock-shafts 4 or secured thereto in any preferred manner. One end of each rock-shaft 4 is bent at a right angle, as shown, to form a handle 4' for partially rotating the shaft, and thereby raising or depressing the spurs 5. When the handles 4' are raised to a vertical position, the spurs 5 are thereby lowered, as shown in dotted lines, to permit a sack to be removed from the spout. When the handles are pushed down to horizontal position, as shown in full lines, the spurs 5 move up and outwardly, and thereby hold the sack in position while it is being filled.

My preferred means for locking the handles 4' in lowered position consists of a spring

6, shaped as shown in Fig. 4 and secured to the front of the spout 1. When the handles 4' are lowered, they impinge upon the inclined face 6' of the spring, pushing in the spring until the shoulder 6'' is passed, when the spring snaps out, leaving the handles 4' held down by the shoulder 6''. To release the handles, an extension 6''' of the spring is pushed in, thereby moving back the shoulder 6'' far enough to permit the handles 4' to be raised.

The operation of the device is as follows: The handles 4' having been placed under the shoulder 6'' of the spring 6, the operator presses the upper edge of the sack upon the spurs 5, which puncture the sack and hold it until it is released. To lower the spurs and release the sack, the operator pushes in the extension 6''' of the spring 6 far enough to permit the handles to turn up. The weight of the filled sack acting on the spurs 5 pulls the handles 4' up to vertical position and becomes released from the spurs.

Having now fully described my invention, what I claim as new, and desire to secure by Letters Patent of the United States, is—

A sack-holder comprising a spout, bearings secured to opposite sides thereof, a pair of rock-shafts supported by said bearings, spurs on said shafts, one end of each rock-shaft being bent at a right angle, said spurs being so arranged that they are elevated when said bent ends are pointed toward each other horizontally, and a detent-spring secured to the spout, said spring having an outwardly and downwardly inclined portion 6' below its attachment to the spout, and having a shoulder 6'' below said inclined portion; said shoulder being adapted to hold down the bent ends of said rock-shafts, substantially as described.

In testimony whereof I affix my signature in the presence of two witnesses.

EDWIN TAYLOR.
